Specification for Design.

Patented Apr. 14, 1914.

Application filed October 23, 1913. Serial No. 796,970. Term of patent 7 years.

To all whom it may concern:

Be it known that we, WILLIAM L. GOLDSTEIN and GEORGE C. VAN ESSEN, citizens of the United States, residing at Saybrook Apartment House, Craft avenue, and 2216 Palm Beach avenue, respectively, Pittsburgh, in the county of Allegheny and State of Pennsylvania, have invented a new and original and ornamental Design for Barbers' Wall-Cases, of which the following is a specification, reference being had to the accompanying drawing, forming part thereof.

The figure is a perspective view of a barber's wall case showing our new design.

We claim:

The ornamental design for a barber's wall case as shown.

WILLIAM L. GOLDSTEIN.
GEORGE C. VAN ESSEN.
